UNITED STATES PATENT OFFICE.

ATWELL J. BLACKFORD, OF CLEVELAND, OHIO, ASSIGNOR TO AMERICAN STOVE COMPANY, OF ST. LOUIS, MISSOURI, A CORPORATION OF NEW JERSEY.

WICKLESS OIL BURNER.

Application filed September 19, 1921. Serial No. 501,709.

To all whom it may concern:

Be it known that I, ATWELL J. BLACKFORD, citizen of the United States, residing at Cleveland, in the county of Cuyahoga and

5 State of Ohio, have invented certain new and useful Improvements in Wickless Oil Burners, of which the following is a specification, reference being had therein to the accompanying drawing.

10 This invention relates to improvements in wickless oil burners and primarily pertains to means for controlling the flame of the burner, and pertains more particularly to wickless blue flame oil burners.

15 Wickless blue flame oil burners comprise essentially an oil trough into which the oil is fed, and a lighting ring seated in the trough for the purpose of lighting the burner and heating it for vaporizing the oil therein, 20 particularly in the starting of the burner, and a combustion section surmounting the trough, consisting of parallel perforated walls between which the vapor rises and partially burns, producing at the top of the 25 combustion section a smokeless blue flame, all of which is well known to those skilled in this art.

In the operation of these burners as heretofore constructed the feed of the oil to the 30 trough has been controlled in various ways for the purpose of regulating the flame. One way has been by the use of the well known needle valve. The well known maintained oil level supply has also been used, in which 35 the amount of oil contained in the trough has been controlled by relatively raising and lowering either the trough or the maintained oil supply.

40 It has been found in the operation of either of the above mentioned ways of controlling the amount of oil in the trough, that the flame does not promptly respond to the regulation of either of the above mentioned ways of controlling the amount of oil in the 45 oil trough. The failure to promptly respond to the oil regulation has been the source of confusion to the ordinary operator, making it difficult to regulate the flame.

The primary object of my present invention is to provide an improved construction 50 for controlling the flame, whereby the flame

promptly responds to the regulating means, thus avoiding any confusion in the hands of operators and enabling them to regulate the flame to the desired height.

55

In carrying out my present improvement I preferably utilize the deep oil trough which in operation contains a considerable quantity of oil, as that type of trough has advantages over the idea of a shallow oil trough, and since the deep trough is best adapted for carrying out my improvement. Where the deep trough is used containing a considerable quantity of oil, the oil tends to cool the trough, and there is a considerable 60 accumulation of carbon at the top of the lighting ring.

65

Another object of my present improvement is to increase the heat at the top of the deep trough, whereby the proper amount of 70 heat is provided to the trough for the best result, and whereby the heat at the top of the trough and at the upper portion of the ring materially decreases the accumulation of carbon on the ring, thereby materially increasing 75 the life of the ring.

Other objects of my invention will appear hereinafter from the description and disclosure thereof.

In the accompanying drawings:

80

Fig. 1 is a side elevation of a stove embodying a burner which contains my present improvements.

Fig. 2 is a vertical central section through a wickless oil burner embodying my improved construction.

85

Fig. 3 is a horizontal sectional view on the line 3—3 of Fig. 2 looking in the direction indicated by arrow.

Fig. 4 is a view similar to Fig. 2, showing 90 a plunger for causing the oil to more rapidly flow from the oil trough, as supplemental to the construction shown in Fig. 2.

Fig. 5 is an enlarged side elevation of regulating means showing it in its various adjusted positions.

95

Fig. 6 is a diagrammatic view showing the trough and the lighting ring in various relative adjustments.

In carrying out my present improvement a 100 suitable stove frame 1 is provided, in which an oil supply pipe 2 is supported at its lower

portion. This supply pipe 2 has one end 3 extending outside of the stove frame and is in communication with the well known maintained oil level device 4.

5 The oil trough 5 is of the deep type and contains a considerable quantity of oil when in operation. Mounted on the upper end of the trough 5 is a well known type of perforated combustion section 6. Since the construction and operation of this combustion section is well known to and understood by those skilled in the art, it is unnecessary to describe it. This combustion section 6 is adapted to be lifted above the trough a suitable distance to expose the lighting ring 18 to be lighted. Any suitable means can be provided for this purpose. As here shown, a vertical movable rod 8 is adapted to engage the combustion section so that it can be 15 lifted, and the lower end of the rod 8 has a laterally extending handle end 9 adapted to engage a suitable hook support 10 when it is elevated, and from which hook it can be disengaged to permit the combustion section to 20 seat on the upper end of the trough.

The bottom of the trough 5 communicates with the supply pipe 2 through a telescoping supply connection comprising an upper tube 11 which has its upper end 12 rigidly connected with the bottom of the trough and in communication therewith, and a lower tubular member 13 which has its lower end fixed to an oil union 14, which is 30 removably connected to a projecting nipple 35 15 by a screw clamp 16. The upper end of the tubular member 13 carries a suitable stuffing box 17, through which the telescoping tubular member 11 moves up and down carrying with it the trough.

40 Located within the trough is the lighting member 18, and its lower end is carried in a suitable metallic holder 19. As shown clearly in Fig. 2, the rod 20 extends through the telescoping tube 11 and the tubular member 13, the lower end 22 of the rod being above the bottom of the opening 23 in the oil union 14.

50 Means for raising and lowering the oil trough 5 and the telescoping tube 11 in the form here shown, comprises a member 24 which has its upper end connected with a bracket 25, and this bracket is attached to the tubular member 11 by solder or otherwise. Preferably this bracket 25 extends 55 across below the bottom of the trough in approximately Z-shape, as shown at 26, and has an opening 27 through which the rod 8 loosely passes the depending extremity of the end 26, forming the aforesaid hook support 10 for the handle end 9 of the rod 8. As here shown, a stay member 28 has its upper end connected to the inner side of the trough and its lower end connected to the Z-shaped portion 26.

60 A vertically arranged combined index and

guide plate 29 is suitably screwed or clamped to an L-shaped plate 30, which plate in turn is fastened to an arm 31 which extends outwardly from the oil union 14. The plate 29 is provided with a vertical slot 32 and a horizontal tube 33 is connected with the lower end of the vertically arranged member 24 through the slot 32 by means of a plate 34 and suitable screws or rivets 35. A shaft 36 is loosely journaled in the tube 33 and carries at its outer end a hand wheel 37 and at its inner end a pinion 38 which meshes with a rack bar 39 attached to the inner side of the plate 29. When the shaft 36 is rotated by the hand wheel 37, the tube 33 with its shaft 36, pinion 38, and vertically arranged member 24, are moved up and down carrying with them the bracket 25, telescoping tube 11 and the trough 5. A suitable pointer 40 projects laterally from the plate 34 and the index plate 29 carries the indications "Out," which would indicate that the burner is in position to be extinguished, the word "Low," which indicates that the burner is in position for low flame, 90 and "Medm," which indicates that the burner is in position for a medium flame, and the word "High," which indicates that the burner is in position for a high flame.

When the burner is in the upper position 95 shown in Fig. 2, there is no oil in the trough and the burner is extinguished. As the burner is lowered the lighting ring which is resting on the bottom of the trough maintains its position in the trough and moves 100 down with it until the lower end of the rod 20 strikes the bottom of the opening 23 in the oil union 14. When this point is reached the downward movement of the rod, the lighting ring holder and the lighting ring is 105 arrested, so that the trough will move downward independent of the lighting ring. By reason of this independent movement the lighting ring changes its position in the trough so that its upper end projects higher 110 in the trough and may even extend beyond the top of the trough when the trough reaches the limit of its downward movement. The distance between the lower end of the rod 20 and the bottom of the opening 115 23 in the oil union 14 will be proportioned to the distance the trough moves above the oil level, and it enables the trough to be lifted high above the oil level. From this it will be seen that the trough and lighting member 120 move downward together until the downward movement of the lighting member is arrested by the lower end of the rod 22, engaging the bottom of the opening 23 in the oil union 14.

125 In Fig. 6 I have diagrammatically shown the relative positions of the trough and the lighting member in four adjustments thereof. In this view the line α represents the bottom of the opening 23 in the oil union 130

14. In the position "H," Fig. 6, the trough is in its lowest position and the lighting member in its relatively highest position, whereby a maximum flame results. In position "M," the trough is raised and the lighting ring is in a lower position in respect to the trough and a medium flame is the result. With the trough and lighting ring in the positions shown in position "L," a low flame is the result and with the trough and lighting ring in the position shown in position "O," the flame is extinguished. Of course it will be understood that there are other adjustments between "H" and "L" 15 in addition to those shown, which would produce flames between "High" and "Medm." and between "Medm." and "Low" though in ordinary operation these three 20 positions are sufficient for all practical purposes.

By means of the relative movement of the trough 5 and lighting ring 18 I am enabled to produce a wickless blue flame oil burner, in which the height of the flame 25 stantly responds to the adjustment of the parts for that purpose.

In a wickless oil burner having the deep trough here shown and containing a large quantity of oil, it is found in practice that 30 the oil cools the walls of the trough and thus reduces the amount of vaporization of the oil, and that also due to the fact that there is not a very high temperature at the top of the lighting ring, there is considerable accumulation of carbon on the lighting 35 ring and thus materially shortens the life of the lighting ring, as well as materially affecting the operation of the burner. For the purpose of producing a high temperature 40 at the top of the trough, thereby increasing the vaporization of the oil, materially reducing the accumulation of carbon on the lighting ring and on the trough, and increasing the life of the lighting ring. I 45 accomplish this increased temperature in the upper portion of the trough by providing its inner and outer walls with a suitable number of properly sized air inlet openings 50 41, which are preferably located below the seats of the walls of the combustion section 6. In this way sufficient air is admitted to maintain a limited combustion in the upper portion of the oil trough, sufficient to produce the above stated functions and 55 accomplish the stated improved results.

In Fig. 4 I have shown a supplemental construction to that shown in Fig. 2, whereby by the oil is caused to more quickly flow out of the trough as it is adjusted vertically. 60 This supplemental construction consists in providing the rod 20 with a plunger 20' within the telescoping tube 11. This plunger 20' is located intermediate the ends of the rod 20 and in this instance a spiral 65 spring 42 surrounds the lower end of the

rod, the upper end of the spring abutting against the lower end of the tube 11 and the lower end of the spring engaging a suitable adjustable nut 43. Like the construction shown in Fig. 2, the lower end 22 of 70 the rod 20 is above the bottom of the opening 23 in the oil union 14, so that the lighting ring and the trough move downward together for a predetermined distance and from that point on the trough moves downward 75 independent of the lighting ring. The object of the spring 42 is to insure the movement of the plunger 20' in the tube 11, as the tube moves upward. By this arrangement there is a suction action on the oil in 80 the trough so that as the trough is elevated the oil will more clearly flow therefrom. To enable the oil to pass by the plunger to the trough in operation, the plunger is provided with one or more longitudinal slots 44 85 which form oil passages, but the same result will be accomplished by making the plunger sufficiently smaller than the interior of the tube 11.

If desired the rod 20 could be cut at the 90 point 45 and made separate from the plunger 20', whereby the ring holder 19 and the ring can be removed from the burner together as they can be in Fig. 2. In this event it is only necessary to provide a stop 95 to limit the outward movement of the plunger 20' and this could be readily accomplished by having a pin or screw pass through the lower end of the tube 11 at the point 46 and extend inward below the lower 100 end of the plunger.

I desire it to be understood that the drawings and description herein are one mechanical expression of my improvement, and that variations and changes therein 105 could be made by those skilled in the art without departing from the spirit and scope of my improvement, sought to be protected herein by the appended claims.

Having thus described my invention what 110 I desire to claim and secure by Letters Patent is:

1. A wickless oil burner, comprising an oil containing member or trough, means for maintaining a body of oil in said trough, a 115 lighting member wholly within the trough, one of said members movable vertically in respect to the other during operation for controlling the flame.

2. A wickless oil burner comprising an oil containing trough, a lighting member wholly within the trough, means for maintaining a body of oil in the trough, the bottom of the lighting member and the bottom 120 of the trough vertically movable during operation, for the purpose described.

3. A wickless oil burner, comprising an oil containing trough, a maintained oil level supply for the trough, a lighting member in the trough, the trough and lighting mem- 130

ber having a relative vertical movement during operation for the purpose of controlling the flame.

4. A wickless oil burner, comprising an oil containing trough, a maintained oil level supply for the trough, a lighting member in the trough, the trough having a vertical movement in relation to the lighting member during the operation of the burner for controlling the flame.

5. A wickless oil burner, comprising an oil trough, a lighting member in the trough, the trough and lighting member movable together a predetermined distance, one of said members vertically movable in respect to the other after said predetermined distance is reached for the purpose described.

6. A wickless oil burner, comprising an oil trough, a lighting member in the trough, said members vertically movable together a predetermined distance and thereafter the trough movable vertically independent of the lighting member.

7. A wickless oil burner, comprising an oil containing trough, a lighting member in the trough, a maintained oil level supply for the trough, the trough and lighting member vertically movable together a predetermined distance in relation to the maintained level oil supply and thereafter one movable vertically independent of the other.

8. A wickless oil burner, comprising an oil trough, a lighting member loosely supported in the trough, the trough and lighting member vertically movable together a predetermined distance, and a stop arresting the downward movement of the lighting member when the predetermined distance is reached.

40 9. A wickless oil burner, comprising an oil trough, a lighting member movably supported in the trough, a vertically movable oil supply pipe connected with the trough, a rod operatively connected with the lighting member and extending loosely through the supply pipe, and a stop for arresting the downward movement of the rod and thereby the lighting ring as the trough moves downward.

50 10. A wickless oil burner, comprising an oil trough, a lighting member vertically movable in the trough, a vertically movable oil supply pipe connected with the trough, a rod extending through the supply pipe and carrying a plunger within the pipe, and means for arresting the downward movement of the rod, thereby causing the plunger to move within the supply pipe.

60 11. A wickless oil burner, comprising an oil trough, a lighting member vertically movable therein, a vertically movable oil supply pipe connected with the trough, a rod extending through the pipe and connected with the lighting member, a plunger car-

ried by the rod within the pipe, means for holding the rod and plunger extended within the pipe and means for arresting the downward movement of the rod and plunger as the supply pipe and trough move downward.

70 12. A wickless oil burner, a vertically movable oil trough, a lighting member movable in the trough, an oil supply pipe, a plunger in the oil supply pipe and means for moving the plunger in the pipe, and the trough and lighting member vertically movable in respect to each other.

75 13. A wickless oil burner, comprising a vertically movable trough, an oil supply conduit therefor, a plunger in the supply conduit and movable therein as the trough moves, thereby accelerating the movement of the oil supply in respect to the trough.

80 14. A wickless oil burner, comprising a vertically movable oil trough, a lighting member movable in the trough, a vertically movable oil supply pipe connected with the trough, a rod connecting with the lighting member and extending through the oil tube, a plunger on the rod within the tube, the rod extending beyond the tube and an expanding spring for holding the rod extended in respect to the oil supply tube for the purpose described.

85 15. A wickless oil burner, comprising a vertically movable oil trough, a lighting member loosely supported in the trough, means connected with the lighting member adapted to arrest the downward movement of the latter, said means disconnected with the movable parts whereby it is removable with the lighting member.

90 16. A wickless oil burner, comprising a vertically movable oil trough, a lighting member movably supported in the trough, an oil supply for the trough, a rod connected with the lighting member and depending in the supply pipe and disconnected, whereby the rod and the lighting member are removable together from the trough.

110 17. In a wickless oil burner, an oil containing trough, a lighting member therein, a combustion section mounted on the trough, the walls of the trough having air openings in constant communication with the atmosphere and with the inside of the trough substantially at the upper end of the lighting member for furnishing air for supplying combustion at the end of the wick during the operation of the burner.

115 18. A wickless oil burner, comprising an oil containing trough, a lighting member therein, a combustion section seated on the upper end of the trough, the inner and outer walls of the trough having air openings in constant communication with the atmosphere and with the inside of the trough adjacent the upper ends but below the lower end of the combustion section for furnishing air

for combustion at the end of the wick, during the operation of the burner

19. In a wickless oil burner, the combination with a main oil supply pipe of an oil union detachably connected with the oil supply, the oil union carrying a vertically adjustable oil trough and a trough raising and lowering means connected with the

trough, whereby the oil union, trough and raising and lowering means form a single **10** attachable and detachable unit for the purpose described.

In testimony whereof I hereunto affix my signature.

ATWELL J. BLACKFORD.
